STATION INDICATOR

Ralph Briney, New York, N. Y.

Application November 5, 1935, Serial No. 48,272

10 Claims. (Cl. 40—53)

This invention relates to station indicators or changeable signs adapted to indicate in railway cars consecutively the next station at which the train will stop.

5 It is the object of this invention to provide an indicator of this type which is mounted in the car and shall automatically and visibly show the name of the next station.

It is a further object of this invention to provide an indicator which is very simple in construction and is very easily installed in the car without extended alterations thereon and which may be operated from the outside thereof by very simple and inexpensive means.

15 It is another object to provide such an indicator that will operate when the car is moving in opposite directions.

With these and other objects in view, the invention consists in certain novel combinations and arrangements of parts which will become clearer as the description progresses and which are illustrated in the accompanying drawings in which—

Fig. 1 is a front view of a station indicator embodying the invention, with the front cover and window removed.

Fig. 2 is a detail sectional view showing the reversing spring mechanism taken on line 2—2 of Fig. 1.

30 Fig. 3 is a detail sectional view on line 3—3 of Fig. 1 showing the reversing gear mechanism.

Fig. 4 is a sectional view on line 4—4 of Fig. 1 showing the starting cam mechanism.

35 Fig. 5 is a sectional view on line 5—5 of Fig. 1 showing the web rolls and brakes.

Fig. 6 is a perspective view of the starting switch mechanism.

Fig. 7 is a perspective view of the reversing switch mechanism.

40 Fig. 8 is a perspective view of the motor brake operating mechanism.

Fig. 9 is a front view on the line 9—9 of Fig. 1 showing the motor brake.

45 Fig. 10 is a sectional detail view on line 10—10 of Fig. 9.

Fig. 11 is a perspective view of the complete station indicator in its casing.

Fig. 12 is a diagram showing the engagement of the operating lever by strikers at the various 50 stations by cars moving in different directions.

Fig. 13 is a view partly in section and partly in elevation showing the operating parts of the improved indicator mechanism in engagement with a striker on a station platform.

55 Referring to Figs. 1 and 11 of the drawings, 50

represents the housing in which the station indicator is enclosed. It is preferably made of sheet metal and of rectangular shape in all three dimensions. The front opening is closed by a sheet metal cover 51 shown in Fig. 11. It is provided with a window 52 behind which the station names appear consecutively. The part 53 of the cover which is not open is preferably used for advertising matter.

Housing 50 is preferably mounted on the top 10 transverse wall of a railway car near the ceiling where it may easily be observed by the passengers. From the right side of the housing 50 near its upper edge as viewed in Fig. 11 a shaft 14 projects. It extends through the wall of the car and its outer end terminates in a two armed handle lever 13 perpendicular to the shaft 14. This handle when turned clockwise operates the indicator mechanism presently to be described.

At the end of each station platform in the system 20 stationary fingers or strikers 47' and 47a are suitably mounted, on posts 48 near the edge of the platform 49 as shown in Fig. 13. These strikers are positioned singly in the path of handle 13 on the moving car so as to be struck thereby when the car moves past it to operate the indicator in order to display the name of the next station in the window.

This indicator mechanism is shown in Fig. 1. It includes a reversible universal electric motor 1 30 adapted to be energized by alternating or direct current. This motor drives a shaft 4 by means of a worm gear speed reducer 2. This shaft is perpendicular to the motor armature and carries at one end a motor brake wheel 3 and at the opposite 35 end a spur gear 5 which meshes with a similar gear 6 driving a shaft 35 mounted in bearings 43. Between these bearings a reversing spring cam 36 is mounted on shaft 35, and on the end opposite to gear 6 a pinion 7 is mounted (Figs. 2 and 3). 40 Pinion 7 meshes with swinging gear 8 shown as adapted to engage drum gear 9a on drum or web-roll shaft 9b on which the web drum 9 is mounted to turn freely in bearings 9c and 9d.

45 This drum 9 carries a web 11 of transparent canvas on which the names of the stations appear consecutively at equally spaced intervals. The web runs over two cylindrical bars or rollers 44 arranged in a plane parallel to the plane of 50 the drum axes and may be rolled from drum 9 on to a second drum 10 mounted to rotate freely in a similar manner parallel to drum 9. Below each drum, a spring 42 is mounted on a bracket 42a on the floor of the housing, which spring acts as a 55

brake against unwarranted unwinding of the web roll thereon.

Between the two drums and below the web a preferably tubular incandescent lamp 12 is mounted in a socket 12a.

From the foregoing description, it will be clear that motor 1 when operating will rotate drum 9 and wind thereon web 11 which unwinds from drum 10 as it is free to rotate in bearings 10c and 10d.

A starting switch 19 controls the supply of current for the motor 1. This switch has its two poles suitably connected by conductors 19a to the terminals of the motor. The switch may be closed by moving the handle 13 clockwise and thereby rotating shaft 14 to which the handle is secured. A crank 14a on the opposite end of shaft 14 will turn a crank shaft 46 by means of a connecting link 45, the shaft being eccentrically mounted in bearing 47 (Fig. 6). The free end of shaft 46 is connected to the movable blades of switch 19 and in this manner the switch is closed and the motor started.

A portion of shaft 46 extends in an opposite direction from bearing 47 and forms a crank 17 swinging in said bearing and carrying at its oscillatable end a grooved wheel 15.

On drum shaft 9b between drum 9 and bearing 9d a cam wheel 16 is mounted (Fig. 4). This cam wheel engages the groove of wheel 15 and a helical tension spring 18, having one end attached to crank 17 and its opposite end suitably fastened to an anchor 18a on the housing wall, urges wheel 15 into contact with the periphery of cam wheel 16. A portion of said periphery is cut away so that during a fixed part of each revolution roller 15 is pulled a distance toward shaft 9b as shown in dotted lines in Fig. 4. The shaft 46 is thus oscillated in a direction opposite to that produced by handle 13 and the switch 19 is opened and motor 1 stopped.

At the corner of housing 50 diagonally opposite to handle 13, a similar handle 31 extends from said housing. This handle is fixed on a shaft 33 which is rotatably mounted in a bearing 32 within the housing and which carries at its inner end a crank 34 connected to the movable blades of a double throw, double pole switch 30 to join either jaw 30a or 30b to the armature conductors 30c for reversing the direction of armature current of motor 1 to reverse its direction of rotation (Fig. 7).

The cam 36 on driving shaft 35 is shown in detail in Fig. 2 and consists of a disk having a notch 40 in its periphery parallel to shaft 35. A shaft 39 is oscillatably mounted in bearings 39a behind shaft 35 and parallel thereto in the same horizontal plane. On shaft 39 two arms 38 and 41 are fastened. Arm 38 carries at its free end a flat spring 37, the end of which leans against the periphery of cam 36. Arm 41 is mounted between drum gears 9a and 10a and carries rotatably mounted at its oscillating upper end a gear 8 adapted to mesh with either gear 9a or 10a and to constantly mesh with pinion 7 on driving shaft 35.

When the operation of motor 1 has been reversed by means of switch 30, the rotation of shaft 35, as indicated by the arrows in Fig. 3 to be counterclockwise, becomes clockwise as indicated in Fig. 2. During the first revolution of shaft 35, the notch 40 of cam 36 engages the end of spring 37 and throws it into the position shown in dotted lines in Fig. 2. Shaft 39 with arm 41 and gear 8 will thereby be oscillated and thus

position gear 8 in mesh with drum gear 10a to rotate said drum in an opposite direction to that of released drum 9.

Between drum 9 and bearing 9c a cam wheel 20 is mounted on shaft 9b (Figs. 1 and 8) to rotate with drum 9. A grooved wheel 24 is mounted on a crank shaft 22 and arranged so that the groove in its periphery is in engagement with the periphery of cam plate 20. Shaft 22 is rotatable in a bearing 22c fastened to the rear plate of housing 50 and has two crank arms thereon indicated at 22a and 22b. Arm 22a carries roller 24, and the free end of the other arm 22b is connected to one end of a horizontal connecting rod 25a which extends from side to side of the housing. A helical tension spring 23 has one end secured to an anchor 54 in the wall of housing 50 and has its other end connected to the arm 22a to urge said arm and roller 24 towards the cam wheel 20. Connecting rod 25a is connected at its other end to a crank 25 which forms part of a horizontal shaft 29 mounted in bearings 28 on the rear wall of the housing 50. At the end of shaft 29 opposite to crank 25, a second crank 26 is formed thereon and extends under an angle therefrom and is provided with a crank pin 26a at its end parallel to shaft 29. This pin is mounted in a loop 27a formed at the end of a metallic brake band 27 (Fig. 9). This brake band is lined inside with a suitable lining 27b which surrounds brake wheel 3 on worm wheel shaft 4 and is pressed thereagainst when crank pin 26a is pressed downwardly.

Cam plate 20 is cut to correspond in shape with cam plate 16 so that when switch 19 is opened by means of plate 16 the roller is simultaneously pushed outward by spring 23 from reduced diameter to the full diameter of the periphery of cam plate 20. Connecting rod 25a is thereby pushed in the direction of the arrow (Fig. 8), crank 25 and shaft 29 are oscillated and crank pin 26a is pushed backward thereby setting brake lining 27b against brake wheel 3 and stopping rotation of shaft 4 instantly.

The electric connections of this station indicator are the standard connections for any reversible direct current series motor and any further description appears to be superfluous.

The cooperation of the various parts heretofore described is as follows:

When a car having the improved station indicator stands still at a station, the station name appears in the window of the indicator on web 11 and is illuminated by the incandescent lamp 12. When the car moves forward the operating handle 13 outside of the car will engage one of the strikers 47 or 47a erected for this purpose. By means of this engagement, shaft 14 is oscillated clockwise closing switch 19 and starting motor 1 thereby rotating drum 9 and cams 16 and 20. A portion of web 11 is wound on drum 9 from drum 10 and the name of the next station is displayed in the window 52. The length of web 11 wound on roller 9 at each operation depends on the length of the arc of the full diameter on cam 16. When the new station name is displayed roller 15 moves into the cam depression and opens switch 19 stopping the motor. Simultaneously roller 24 is pressed outward by cam 20 and thereby brake 3 is set and prevents overrun. This operation is repeated at the start of car from every station until the end of the line is reached.

Before the return trip is started in the opposite direction on the opposite track, lever handle 31 is 75

turned whereby reversing switch 30 is closed. This may be done by the conductor or automatically by extending shaft 33 to the outside of the car and by mounting handle 31 on the outside 5 of the car wall with its end in position to be struck by a suitable striker 47' or 47a mounted in its path. When handle 31 is actuated the drum which was idling before will then be driven by gear 8 which has automatically been placed 10 in mesh with its drum gear by the action of reversing cam 36, spring 37 and lever 38.

The placing of striker arms at station platforms has to be so arranged that when the car 15 54 is moving in either direction lever 13 is operated clockwise. For this purpose these strikers are arranged higher on the outgoing track than the return track to strike either the upper or the lower arm of handle 13. For example, as shown 20 diagrammatically in Fig. 12, the lower arm of handle 13 may strike the striker arm 47a on the outgoing run, and its upper arm may strike the striker arm 47' on its return run. Of course, it 25 will be understood that these striker arms may be placed along the respective tracks either on the outside or inside as required.

Having thus described my invention, I want it 30 to be understood that changes in details of construction may be made without departing from the principle of the invention and I desire to be limited only by the state of the prior art and the appended claims.

I claim:

1. A station indicator including a housing having 35 a window in one of its sides, a pair of drums in said housing, a web on said drums having a part thereof in said window, electric motor operated means to rotate one of said drums and a cam fastened to said drum and a switch for starting and stopping said motor operated by said 40 cam forming means to wind a fixed portion of said web upon said drum while unwinding it from the other drum.

2. A station indicator including a housing, an 45 electric motor, a pair of drums in said housing, a web carried by said drums to be wound from one drum to the other, a spur gear on each drum, an oscillatable pinion mounted between said 50 gears to engage either gear separately to transmit rotary motion to either one of said drums and means operated by said motor to oscillate said pinion for changing the direction of rotation of said drums.

3. In a station indicator a pair of rotatable 55 drums, a web on said drums adapted to be wound from one drum on to the other, an electric motor of the reversible type, a shaft operated by said motor, an operating gear on said shaft, a gear on each drum adapted to be operatively connected 60 to said operating gear by an idler pinion oscillatably mounted between said drum gears and a cam on said shaft forming means to oscillate said pinion to separate its mesh with the gear of one drum and place it in mesh with the gear of the other drum by reversing the rotation of said motor.

4. In a station indicator, a housing, an electric motor, a pair of drums in said housing parallel 70 to each other, a web on said drums adapted to be wound from one drum on to the other, a shaft passing through one wall of said housing having a crank mounted thereon at its outer end, a switch in said housing connected to the terminals of said motor, means on said shaft for

closing said switch, a cam on one of said drums, a roller operated by said cams and means connecting said roller with said shaft for opening said switch.

5. In a station indicator, a pair of rotatable 5 drums parallel to each other, a web on said drums adapted to be wound from one drum upon the other, a pair of cams adapted to rotate with one of said drums, an electric motor for rotating said drum, a brake for said motor, a pair of rollers, each roller mounted for operation by one of said cams, a switch for operating said motor, means operatively connected to one of said rollers and to said switch for operation of said motor by said switch and other means operatively 10 connected to the second roller for operation of said brake by means of the second cam.

6. In combination, a railway car having mounted therein a station indicator, a housing for said indicator, an electric motor and a pair 20 of drums within said housing, a web on said drums adapted to be wound from one drum on to the other by means of said motor, a switch in said housing, a shaft operatively connected to said switch extending through a wall of said housing 25 and through a wall of said car, a lever at the outside end of said shaft, a stationary support mounted outside of said car having a striker arm fixed thereon in the path of said lever forming means to operate said switch by striking said 30 striker arm when said car is in motion.

7. In combination, a railway car having mounted therein a housing, a station indicator comprising a pair of drums, a web on said drums adapted to be wound from one drum on to the 35 other, a reversible motor operatively connected to one of said drums, a switch for reversing the rotation of said motor, a shaft operatively connected to said switch extending through a wall of said housing and through a wall of said car, 40 a lever on the outside end of said shaft, a stationary support mounted outside of said car having a striker arm fixed thereon in the path of said lever forming means to operate said switch by striking said 45 striker arm when said car is in motion to reverse the rotation of said motor.

8. In combination, a railway car having mounted therein a housing, a device in said housing adapted to display consecutively on said housing a plurality of signs, a motor in said housing for operating said device, a pair of shafts extending from said device in opposite directions through opposite walls of said housing and through opposite walls of said car, a lever on each 55 of said shafts, stationary supports mounted on the outside of said car and a striker arm on each of said supports in the path of movement of said levers and adapted to engage the same, one of said striker arms being adapted to start said 60 motor by engaging one of said levers, the other striker arm being adapted to engage the other lever to reverse the rotation of motor when said car is in motion.

9. A station indicating system for railways 65 comprising in combination with a stationary platform having a stationary protruding member, a movable web bearing station indicia in the car, means including a motor for actuating said web a predetermined distance and a member 70 protruding from the car and adapted to be struck by said stationary protruding member for starting said motor.

10. A station indicating device for railways 75 including a movable web bearing station indicia,

and mechanism for moving said web a predetermined distance, said mechanism including a reversible motor, a train of gearing interposed between the motor and web support, a switch for 5 said motor, a switch member protruding exteriorly of the railway car and adapted to strike a stationary member on the station platform for

closing said switch, and another switch member protruding exteriorly of the car adapted to be operated by hand or automatically by striking a stationary member on the station platform to close the switch and reverse the motor. 5

RALPH BRINEY.
